US0D1076348S

(12) United States Design Patent (10) Patent No.: US D1,076,348 S
(45) Date of Patent: * May 27, 2025

(54) BILL GUARD

(71) Applicant: Corey Pendergraft, Leesburg, FL (US)

(72) Inventor: Corey Pendergraft, Leesburg, FL (US)

() Term: 15 Years

(21) Appl. No.: 29/836,322

(22) Filed: Apr. 26, 2022

(51) LOC (15) Cl. 02-03

(52) U.S. Cl.

USPC D2/891; D2/893

(58) Field of Classification Search

USPC D2/865, 866, 872, 882, 886; D20/11, 22,

D20/32; D29/102, 103

CPC A42B 1/00; A42B 1/008; A42B 1/002;

A42B 1/004; A42B 1/006; A42B 1/062;

A42B 1/201; A42B 3/00; A42B 3/124;

A42C 5/00
